UNITED STATES PATENT OFFICE.

JOSEPH R. DUMONT, OF KANSAS CITY, MISSOURI, ASSIGNOR TO MAUDE FRANCES DUMONT, OF KANSAS CITY, MISSOURI.

LOCK.

Application filed January 15, 1925. Serial No. 2,585.

To all whom it may concern:

Be it known that I, JOSEPH R. DUMONT, a citizen of the United States, residing at Kansas City, in the county of Jackson and State of Missouri, have invented certain new and useful Improvements in Locks; and I do declare the following to be a full, clear, and exact description of the invention, such as will enable others skilled in the art to 5 which it appertains to make and use the same, reference being had to the accompanying drawings, and to the figures of reference marked thereon, which form a part of this application.

This invention relates to locks and particularly to that class of locks used for locking the doors of compartments of rest rooms or public comfort rooms. The bolts of such locks are usually releasable upon the introduction of a check, coin or token of appropriate denomination, but unscrupulous persons not infrequently pry back the bolt with a knife or thin piece of metal.

My invention contemplates the provision of means for rendering it impossible to retract the bolt except in a legal manner, the legal way consisting of introducing a proper coin or token into the lock case.

The case is a continuation, in part, of an application filed by me January 15, 1923, Serial No. 612,636, in which I described substantially the same mechanism for preventing the unauthorized retraction of the bolt by hair pins, shoe buttoners or similar devices, but in the specific embodiment of that part of the invention shown in the drawings, I have departed slightly from the exact details shown in the former application although the principle involved and the generic configuration of the detent is followed in the present application.

Inasmuch as the coin controlling and actuating mechanism is so fully described in my former application and in view of the fact that this invention has to do only with the bolt actuating mechanism, I have deemed it to be unnecessary to re-describe all of the coin controlling mechanism of my former application, rather will I confine it to the elements to be claimed.

In the drawings:

Fig. 1 is a front elevational view of the lock, part of the case being broken away.

Fig. 2 is a cross sectional view through the case. 55

Fig. 3 is an elevational view of the locking mechanism with the front cover plate removed.

Fig. 4 is an elevational view of the rear side with the cover plate removed. 60

Fig. 5 is a perspective view of the rocking lever and the latch bar, and

Fig. 6 is a perspective view of the latch bar releasing lever and the locking bolt. 65

The main locking bolt 1 is slideable in the case 2 in the usual way and as is usual with such locks it is normally urged into projected or keeper engaging position by a spring 3. The locking bolt 1 is retractable by a rocking lever 4 which has a stud or pin 5 on it, normally lying against the edge 6 of a vertical sliding member 7. The sliding member has an offset groove or recess 8 normally out of line with the pin 5 so that the rocking lever cannot swing on its pivot 9. 70 There is mechanism provided in the lock for causing the pin 10 to move in the slot 11 to raise the slide 7 when a coin, check or token is inserted in the lock case, the raising of the slide being effective in bringing the off-set groove 8 in line with the pin 5 so that the pin can swing through the lock or recess and since this permits the rocking lever to be actuated by the knob spindle 12 and the fingers 13 and 14, it will be apparent that 75 the bolt 1 can be retracted because the finger 15 on the rocking lever 4 engages a lug 15' on the bolt 1, consequently a swinging movement of the rocking lever in one direction will retract the bolt. This, or similar mechanism, is shown in my former application 80 above referred to.

It will be observed, both from my former application and the present case, that unless some means is provided for preventing the surreptitious retraction of the bolt 1, the lock could be illegally operated so I have provided a detent normally in the path of movement of the bolt 1. The detent is designated 16 and it consists of an elbow lever having a hooked end 17 normally lying against the rear end 18 of the bolt 1 so that the bolt cannot be withdrawn except when the rocking lever 4 is actuated. The hooked end 17 is normally urged into functional 95 position by a flat spring 19, one end of which 100

is fixed to the case and the other end of which bears against the elbow lever or detent 16. By referring to Fig. 4 it will be observed that the detent is pivoted to the 5 case at 21 and that it has a downwardly curved finger 22 lying in a slot or cut away portion 24. In the transverse sliding bolt 25 normally urged outwardly by a spring 26, one end of which bears against the bolt 10 25 and the other end of which bears against the guide stud 27 for the stem 28 of the bolt 25. The bolt 25 projects from the case so that in the event that some one attempts 15 to tamper with the lock by introducing a knife blade, shoe buttoner or other operating means in front of the bolt 25, the bolt 25 will be pushed rearwardly so that it will hit or press against the end of the finger 22 and thereby press the hook 17 into detaining 20 position with respect to the bolt 1, consequently the bolt 1 cannot be retracted until the rocking lever is turned or swung about its pivot 9. The rocking lever 4 cannot be turned until the coin is introduced, as has 25 been clearly described in my former application above referred to, when the slide member 7 is raised to bring the off-set 8 in line with the pin 5. This can be accomplished when the rocking lever is swung 30 back. The terminal or end 29 on the rocking lever will ride on the cam 30 of the detent to swing the hooked end 17 out of line with the bolt 1 just before the finger 15 rides on the rear end of the slot of the bolt 35 1 through which it projects, consequently the bolt 1 may be withdrawn.

It is to be understood that when the door is closed that the bolt 25 bears against the face of the keeper in the frame so that the 40 spring 26 is compressed and that when the door is open the spring extends or expands so that the bolt 25 may be projected forwardly and it is to be understood furthermore, that when the slide 7 is in its raised 45 position to allow the offset 8 to align with the pin 5 it is held in that position by a latch or pawl 31 which engages the notch 32 of the slide 7 to hold the slide in its raised position. When, however, the door is 50 closed and the bolt 25 is retracted back in the lock, because its end 33 rides on the door jam, the rearward movement of the bolt 25 will impart a rearward movement of the spring arm 34 rigidly carried by the bolt 25 55 through the medium of the bracket 35. The rearward movement of the spring will cause its end to strike a pin 36 on the pawl 31 pivoted at 37 to retract the pawl out of the notch 32, then the slide may drop into its 60 original position to be raised only when a check, coin or token is introduced into the machine, this being effective in raising the pin 10. The pawl 31 will be thrown over into sliding engagement by the pivoted indicator 38 and the link 39.

The means for operating the indicator has all been described in my former application above referred to.

It will be apparent from the foregoing 70 that the main locking bolt cannot be retracted by unauthorized persons due to the fact that the detent will effectively prevent this and the detent can be actuated by a supplementary bolt which will also be effective in disengaging the pawl 31 from the vertical slide member.

What I claim and desire to secure by Letters-Patent is:—

1. A lock comprising a casing, a locking bolt in the casing, means for normally urging the locking bolt into locking position, a detent having a hooked end normally urged into the path of movement of the locking bolt to prevent its retraction, a supplemental bolt for actuating the detent to retain the hooked end away from the path of movement of the locking bolt when the supplemental bolt is in projected position and to permit the hooked end to move into the path of movement of the locking bolt when the supplemental bolt is moved to retracting position, and means for normally urging the supplemental bolt out of retracting position. 80 85 90

2. A lock comprising a casing, a locking bolt in the casing, means for normally urging the locking bolt into locking position, a detent having a hooked end normally urged into the path of movement of the locking bolt to prevent its retraction, a supplemental bolt for actuating the detent to retain the hooked end away from the path of movement of the locking bolt when the supplemental bolt is in projected position and to permit the hooked end to move into the path of movement of the locking bolt when the supplemental bolt is moved in one direction and means for moving the bolt in the opposite direction, said means being effective in moving the supplemental bolt out of operative relation with respect to the detent. 95 100 105 110

3. A lock comprising a casing, a locking bolt in the casing, the bolt having a shank, means for normally urging the locking bolt into locking position, a detent having a hooked end normally urged to a position in rear of the free end of the shank of the bolt in the path of movement of the locking bolt to prevent its retraction, a supplemental bolt for actuating the detent and means for retracting the locking bolt, said means being effective in moving the hooked end out of the path of movement of the locking bolt. 115 120

4. A lock comprising a casing, a slideable locking bolt in the casing, the bolt having a shank, means for normally urging the locking bolt into locking position, a detent having a hooked end movable in rear of the free end of the shank for holding the locking bolt against retraction, 125 130

- a supplemental bolt having means for moving the detent in position for holding the locking bolt against retraction, and a spring normally urging the supplemental bolt out 5 of functional relation with the detent.
5. A lock comprising a casing, a locking bolt in the casing having a slot therein, means for normally urging the lock into locking position, a detent having means for 10 holding the locking bolt to prevent retraction, a supplemental bolt for actuating the detent, and means for retracting the bolt including a member passing through the slot in the bolt engaging with the detent to 15 throw the detent out of engagement with the bolt prior to retracting movement of the bolt.
6. A lock comprising a casing, a locking bolt in the casing having a slot therethrough, 20 means for normally urging the locking bolt into locking position, a detent normally urged in the path of movement of the locking bolt to prevent its retraction, a supplemental bolt for actuating the detent, and 25 means for retracting the locking bolt com-
- prising a rocking member having a finger projecting through the slot in the locking bolt, contactable with a part on the detent to move the detent out of locking bolt engaging position prior to retracting movement of the locking bolt. 30
7. A lock case, a locking bolt in the case, a retracting element for the locking bolt having a pin, a sliding stop member normally lying in the path of the pin, the stop member having an offset portion through which the pin may pass when the stop member is moved longitudinally, a pawl, a detent for holding the stop member in raised position, means for urging the locking bolt into functional position, a detent for holding the locking bolt against retraction, a supplemental bolt for actuating the detent, and means on the supplemental bolt for moving the pawl out of engagement with the stop member. 35 40 45

In testimony whereof I affix my signature.

JOSEPH R. DUMONT.
